UNITED STATES PATENT OFFICE

MAXWELL ALPERN, OF PHILADELPHIA, PENNSYLVANIA, ASSIGNOR TO AMERICAN ENGINEERING COMPANY, OF PHILADELPHIA, PENNSYLVANIA, A CORPORATION OF PENNSYLVANIA

FUEL FEEDING MECHANISM FOR MECHANICAL STOKERS

Application filed September 29, 1926. Serial No. 138,469.

My invention relates to furnaces, and it has particular relation to stokers.

In its broad aspect, the object of my invention is to provide a stoker, wherein a greater or less amount of fuel may be fed to any desired part of the fire, or a greater or less amount of ashes fed from the furnace bed.

A more specific object of my invention is to provide a stoker retort, wherein one wall thereof shall substantially comprise a plurality of independently adjustable pushers, so that fuel may be fed to any part of the furnace at a greater average rate than any other part thereof.

Another object of my invention is to provide stoker apparatus comprising a plurality of pushers constituting one wall of a retort, means whereby the position of the path of travel of at least one of the pushers may be adjusted independently of that of the others, and means whereby the throw of one or more of the pushers may be independently adjusted.

A further object of my invention is to provide a stoker wherein adjacent pushers in any part of the retort may have different strokes, so that a desired slicing effect may be had on the fuel.

Other objects and applications of my invention, as well as details of construction and operation, whereby my invention may be practiced, will appear more fully hereinafter, when taken in connection with the accompanying drawings, wherein

Fig. 1 is a longitudinal sectional view of an inclined underfeed stoker embodying my invention, the sectional plane being taken on the line 1—1 of Fig. 2, the primary and secondary pushers being illustrated in their maximum advanced positions;

Fig. 2 is a partial bottom plan view of the structure of Fig. 1;

Fig. 3 is an enlarged detail view, partially in longitudinal section and partially in elevation of the lost-motion connection between the pusher and the operating mechanism, the sectional plane being taken on the line 3—3 of Fig. 4;

Fig. 4 is a similar view, the sectional plane being taken on the line 4—4 of Fig. 3;

Fig. 5 is an enlarged detail end elevational view of the mechanism for independently adjusting the stroke of the pusher groups, the sectional plane being taken on the line 5—5 of Fig. 1; and

Fig. 6 is an enlarged, longitudinal sectional view of the stroke-adjusting mechanism of Fig. 5 and connected parts taken on the line 6—6 of Fig. 2.

In the illustrated embodiment of my invention shown in the drawings, a furnace 1 comprises a stoker 2 of the inclined underfeed type and it is provided with any desired number of series of tuyères 3 which extend downwardly from a fuel opening 4 in a furnace front wall to a rear end 6 of said furnace. Between each pair of series of tuyères 3 is positioned a stoker retort 7, an upper end 8 of which terminates in the fuel opening 4. This opening may be supplied with fuel from a hopper 9 which delivers into a casing 11 communicating directly with the retort entrance 4. Fuel from the hopper 9 may be forcibly fed through the retort opening 4 by means of a primary pusher 12 which is slidably mounted in the casing 11. A lower rear end 13 of the retort 7 is operatively associated with an extension grate 14 slidably mounted on a framework 15 which also serves to support the series of tuyères 3.

A desired portion 16 of a retort bottom wall 17 may comprise a series of secondary pushers 18 which are slidably mounted in stepped relation on guides 19 supported by spaced side plates 21, as illustrated in my Patent No. 1,443,202, granted to the American Engineering Company January 23, 1923. The present pushers 18, however, embody the further feature of a scraping bar 22 which serves to prevent the escape of siftings between adjacent pushers as well as the jamming of the pushers 18 on their slides 19 due to accumulations of siftings. As shown in Fig. 1, the scraper bar 22 may be loosely positioned in a transversely extending groove 23 on the underside of the pusher 18 and it is provided with a bevel edge 24 to facilitate the scraping action.

Heretofore, when feeding fuel into fur-

naces, either on grates or through underfeed retorts, it has been the practice to have a graduated feed from the front to the rear of the stoker or from the rear to the front. 5 In such constructions, should the fuel bed become too thin at any point, as a result of the character of the coal or through an error on the part of the operator, it is not possible to feed more fuel directly to that point 10 and thereby fill the hole. Furthermore, such constructions do not permit relative movements of the fuel which serve to assist both the rate and efficiency of fuel burning. Thus, it has been found that for certain fuels, 15 by reason of the high clinkерage tendency of the ash and the high percentage of ash in the fuel, the rate of feed at the rear end of the stoker should be greatly in excess of that at any other point. Experience has shown 20 that with fuels of this character, not infrequently it is very desirable to have adjacent pushers operate at different average rates in order to obtain a slicing effect on the fuel by such relative movement.

25 As a result of my present invention, the above problems have been satisfactorily solved, so that a greater or less amount of fuel may be fed to any desired part of the furnace and a greater or less amount of ash fed therefrom. The apparatus for accomplishing these desired results comprises, in addition to the aforesaid parts, a plurality of individual driving or power-transmitting means 25, 26 and 27 for independent secondary pusher units 28, 29 and 31, respectively, 30 the several driving means having lost-motion connections 32, 33 and 34 with a common actuating mechanism 35 which has a lost-motion connection 36 with the primary fuel pusher 12, all as will appear in greater detail 35 hereinafter.

The intermediate and front pusher units 28 and 29 may each comprise three pushers and the same may be true of the rear unit 31, 40 but only one pusher has been here shown. Each of the pushers 18 is provided with an integral rack 37 (Figs. 3 and 4) which is cast on a front underside portion 38 thereof, and it is engaged by a segmental gear 39 mounted 45 on a pin 41 supported by bearings 42 extending from the side plates 21. A lever 43 is provided with spaced end portions 44 which are mounted on the pin 41 on opposite sides of the segmental gear 39. The lever 43 is also provided with an intermediate portion 45 forming a shoulder 46 adapted to abut against a corresponding shoulder 47 on the segmental gear 39 when the secondary pusher 18 is to be projected rearwardly into the retort 7 and the fuel advanced from the bottom of said retort.

50 The segmental gear 39 is further provided with an adjustable abutment 48 in the form of a bolt 49 which is threaded in a lug 50 of the segmental gear 39 and terminates in

an adjusting handle 51. The adjustable abutment 48 is positioned to engage the intermediate portion 45 of the lever 43 when the secondary pusher 18 is to be returned from its projected position shown in Fig. 1 to its front or retracted position. The bolt 49 thus provides an adjustable lost-motion connection 52 between the operating lever 43 and the secondary pusher 18, whereby the stroke or fuel feeding rate thereof may be 55 varied from zero to a maximum value determined by the movement of the operating lever 43. Since each of the secondary pushers 18 is provided with such operating mechanism, the stroke or throw of the 60 pushers in each group may be independently adjusted and such adjustment will not affect the stroke of the individual pushers in the other groups. Therefore, the stroke of any pusher 18 may be increased to a value greater 65 than that of each of the other secondary pushers.

An opposite end 53 of the operating lever 43 is also bifurcated to receive therebetween an operating member or link 54 and it is 70 connected thereto by means of a pivot pin 55. The operating member 54 is used in connection with the intermediate pusher group 28 and the outer pusher group 29, whereby the levers 43 of these groups may be simultaneously operated. The single pusher in the rear or inner unit 31 is also provided with a somewhat similar operating member 56 having a pivotal connection 57 to an inner end 58 of a link 59, an opposite end 61 of which 75 is pivotally connected to an adjacent end 62 of a rod 63 which is slidably mounted at said end in a bracket 64 supported by the side plates 21. The end 58 of the link 59 is also connected to the movable extension grate 14 by means of a centrally pivoted lever 65, a link 66, and an extension grate rod 67. The movement of the link 59 thus causes the 80 operation of the extension grate 14 and the rear pusher unit 31. The stroke of the latter 85 may be adjusted independently of the extension grate 14 by reason of the lost-motion connection 52.

As shown in Fig. 2, the link 59 preferably 90 comprises a central member 68, opposite ends of which are respectively positioned in threaded borings formed in end members 71 and 72, whereby the overall length thereof may be varied should it be desirable to adjust the position of the extension grate 14 and the rear pusher unit 31 with respect to the remaining pusher units.

The operating member 54 of the intermediate pusher group 28 is provided with a bracket 73 which may be moved longitudinally thereof from one desired position to another. The bracket 73 provides a pivotal mounting for one end 74 of a link 75, an opposite end 76 of which is pivotally connected 100 to an inner end 77 of a rod 78 slidably 105

mounted in a bearing afforded by the bracket 64. Such longitudinal adjustment of the bracket 73 permits the position of the path of travel of the intermediate pusher unit 28 to be varied relative to that of the other pusher units.

The front pusher group 29 adjacent to the fuel entrance 4 is somewhat similarly connected by a link 79 to a sleeve 81 which is 10 adjustably mounted on a rod 82 slidably mounted in a third bearing afforded by the bracket 64. The adjustment of the sleeve 81 on the rod 82 accomplishes the same purpose as the adjustment of the bracket 73 on the operating member 54 of the intermediate pusher group 28.

The longitudinally slidable rods 63, 78 and 82 are preferably supported by the bracket 64 in a common plane. These rods are similarly supported in bearings 83 (Figs. 1 and 20) provided by a lower section 84 of a two-part housing 85, an upper section 86 of which is removably clamped to said lower part by bolts 87 (Fig. 5). Each of the slidable rods 25 has an extended portion 88 of reduced diameter providing a shoulder 89 at one end and terminating in a threaded portion 91 at the other end. The threaded ends 91 of the rods 78, 82 and 63 are respectively provided with 30 adjustable abutments 92, 93 and 94, (Fig. 5).

A lower rack 95, which is slidably mounted in the walls of the lower housing section 84, is provided with apertures 96 through which the shaft extensions 88 respectively extend.

35 When the lower rack 95 is moved rearwardly, it engages the shoulders 89 of the rods 78, 82 and 63 and when the rack 95 is moved in the opposite direction, it engages the outer adjustable abutments 92, 93 and 94 of the 40 respective rods just mentioned. The lower rack 95, which thus serves as a common operating member for the independent driving means 25, 26 and 27, constitutes one part of the reciprocable actuating mechanism 35.

45 Under conditions of operation, when the several secondary pushers 18 are withdrawn from the retort 7 to the desired extent, as determined by the adjustable members 81, 73, and 68, the lower rack 95 is in its extreme 50 rear position and in engagement with the shoulders 89 of the several rods 78, 82 and 63. When the lower rack 95 is in its extreme outer position, as shown in Fig. 1, it is in engagement with the outer adjustable abutments 92, 93 and 94 and the secondary pushers 55 18 occupy their extreme rear or projected positions.

When it is desired to vary the stroke or throw of any one of the rods 78, 82 and 63 independently of each of the others, the outer adjustable abutment of said rod is moved to a new position. For example, should it be desirable to cause the intermediate pusher group 28 to have a greater stroke than that of 65 the other groups, the outer abutment 92 is

so turned as to decrease the lost-motion connection 32 between its rod 78 and the rack 95. Such adjustment in no way affects the individual adjustment of the pushers in said intermediate group 28 or the remaining groups 70 and a further independent adjustment may be made at the pushers by means of their lost-motion connections 52, so that, for example, only one of the pushers of said intermediate group is actuated. Similar adjustments may 75 be made for the remaining groups. The stroke of the extension grate 14 may be controlled independently of the rear pusher unit 31 by properly adjusting the rod abutment 94 and the lost-motion connection 52 at the 80 pusher.

The lower rack 95 may be actuated by means of a pinion 97 which is mounted on a shaft 98 supported by the two-part housing 85, the pinion being actuated by an upper 85 rack 99 slidably mounted in the walls of the upper housing section 86. The racks 95 and 99 and the pinion 97 constitute the essential elements of the reciprocatory actuating mechanism 35. The upper rack 99 is apertured to receive a threaded end 101 of a pusher-rod 102 having spaced abutments 103 and 104 positioned in the path of travel of a shoulder portion 105 of the primary pusher 12, thereby forming the lost-motion connection 90 36. The outer abutment 104 may be adjustably mounted on the pusher-rod 102, whereby the stroke of the lower rack and consequently that of all the secondary pushers 95 18 may be simultaneously varied at will. 100

Assuming the secondary pushers 18 to be in the projected position shown in Fig. 1 and the several rod abutments 92, 93 and 94 so adjusted that the strokes of their corresponding rods are equal, a forward movement of 105 the primary pusher 12 from engagement with the inner abutment 103 into engagement with the outer abutment 104 causes no operation of the secondary pushers 18 by reason of the lost-motion connection 36 at this point. A further movement of the primary pusher 12, however,

causes the abutment 104 to be actuated for the remainder of the stroke of said primary pusher. The resulting movement of the pusher-rod 102 causes an opposite movement of the lower rack 95 from engagement with the several rod abutments 92, 93 and 94 into engagement with the inner shoulders 89 thereof. The continued movement of the lower rack 95 for the remainder of its stroke causes 110 a forward movement of the pusher units 28, 29 and 30, the point at which the individual pushers 18 of these groups are actuated being determined by the lost-motion connections 115 52. When the primary pusher 12 is moved in

the opposite direction to feed fuel from the hopper 9 through the opening 4 into the retort 7, the several pushers 18 are projected into the retort 7 at intervals determined by the setting of the shaft abutments 92, 93 and 120 94. 125

94 and the adjustable abutments 48, so that fuel may be fed to any part of the furnace fire at a greater rate than any of the other parts or the ashes may be fed therefrom at a 5 greater or less rate.

While I have shown only one embodiment of my invention, for the purpose of describing the same and illustrating its principles of construction and operation, it is apparent 10 that various changes and modifications may be made therein without departing from the spirit of my invention, and I desire, therefore, that only such limitations shall be imposed thereon as are indicated in the appended 15 claims or as are demanded by the prior art.

I claim:

1. A stoker retort having a series of groups of pushers constituting the bottom of said retort, means whereby the strokes of said 20 groups of pushers may be relatively adjusted and the strokes of the pushers in each group may be adjusted, individual motion-transmitting means for said groups, and common actuating means for said individual motion-transmitting means.

2. A stoker having a retort provided with at least two groups of pushers, individual driving means for said groups of pushers, the pushers in each group having lost-motion 30 connections to their individual driving means, a primary pusher, and means for so connecting said individual driving means and said primary pusher that the stroke of said individual driving means may be independently controlled and the stroke of each 35 of said pusher groups as a whole varied thereby.

3. A retort provided with a plurality of groups of pushers constituting a movable bottom wall thereof, individual power-transmitting means for said groups, the connection between each power-transmitting means and its respective group being such that the stroke of one of the pushers in said last-mentioned 40 group may be varied independently of that of the others, primary actuating means, and means connecting said last-mentioned means and said individual power-transmitting means whereby the stroke of the latter may be independently controlled and the stroke of each of the groups of pushers as a whole varied thereby.

4. In an underfeed stoker, a retort having a secondary pusher, a primary pusher for feeding fuel into said retort, a rack having a lost-motion connection to said primary pusher, a second rack, a gear for operatively connecting said racks, and means for operatively associating said second rack and said secondary 50 pusher whereby the stroke of the latter may be adjusted adjacent to said second rack and also adjusted in proximity to said secondary pusher.

5. In combination, a plurality of groups of 55 pushers, each pusher having a rack, a gear

for actuating said rack and a lever having a lost-motion connection to said gear, a common operating member for the levers of each group, actuating means, a rack driven thereby, and linkage for so connecting said driven rack and said groups that the average fuel feeding rate of the latter may be independently adjusted.

6. In combination, a plurality of groups of pushers, each pusher having a rack, a gear positioned to engage said rack and a lever having a lost-motion connection to said gear, a common operating member for the levers of each group, actuating means, a rack driven thereby, a plurality of rods having independently adjustable lost-motion connections to said driven rack, and linkage for respectively connecting said rods and said operating members.

7. A furnace having a stoker provided with a plurality of groups of pushers, each pusher having a rack, a gear in mesh with said rack and a lever having a lost-motion connection to said gear, a common operating member for the levers of each group, actuating means, a rack driven thereby, a plurality of rods having independently adjustable lost-motion connections to said driven rack, and means including linkage whereby said rods and said respective operating members 55 may be adjustably connected.

8. A stoker having a fuel retort, a plurality of pushers movable in the bottom of said retort, mechanism for actuating said pushers, motion-transmitting means connecting the pushers with said mechanism, said transmitting means including adjustable means for regulating the stroke of a plurality of said pushers as a unit, and independent means for individually adjusting the stroke of at least one of said pushers within said unitary group.

9. A stoker having a fuel retort, a plurality of pushers movable in the bottom of said retort, mechanism for actuating said pushers, motion-transmitting means for connecting the pushers and said mechanism, said transmitting means including adjustment means affecting the stroke of a plurality of said pushers as a group, and independent adjustment means affecting the stroke of an individual pusher of said group.

10. A stoker having a fuel retort, a plurality of pushers movable in the bottom of said retort, mechanism for actuating said pushers, motion-transmitting means connecting the pushers and said mechanism, said transmitting means including adjustment means for regulating the length of stroke of a plurality of said pushers as a group, other means for regulating the lengths of the strokes of the individual pushers within said group, and adjustment means also included in said transmitting means for determining the paths in which the said strokes occur.

11. A stoker having a fuel retort, a plurality of pushers movable in the bottom of said retort, said pushers being actuatable in groups, a common actuating mechanism, and means for connecting the mechanism with said groups, said connecting means including adjustment means for regulating the strokes of said groups, adjustment means also included in said connecting means for individually regulating the strokes of the pushers of the respective groups, and other adjustment means for determining the relative positions of said groups.

12. A furnace having a stoker provided with a plurality of groups of pushers, mechanism for actuating said pushers, means connecting the pushers with said mechanism, said connecting means including adjustment means for independently regulating the length of stroke of the individual groups, and other adjustment means confined to the individual groups for regulating the strokes of the individual pushers.

13. A furnace having a stoker provided with a plurality of groups of pushers, a common operating member for the pushers of each group, adjustable connections between the operating members and the pushers of the respective groups affording independent regulation of the strokes of the individual pushers, actuating means, and means for independently connecting said operating members with said actuating means, said last-named connecting means being adjustable to independently regulate the length of the strokes of the individual groups.

14. A furnace having a stoker provided with a plurality of groups of pushers, a common operating member for the pushers of each group, adjustable connections between the operating members and the pushers of the respective groups affording independent regulation of the strokes of the individual pushers, actuating means, means for independently connecting said operating members with said actuating means, said last-named connecting means being adjustable to independently regulate the length of the strokes of the individual groups, and adjustment means also associated with the said last-named connecting means for independently regulating the paths in which the said groups are movable.

MAXWELL ALPERN.
